UNITED STATES PATENT OFFICE.

WILLIAM G. JACKSON, OF LOS ANGELES, CALIFORNIA, ASSIGNOR TO EMPIRE CHINA COMPANY, OF BURBANK, CALIFORNIA, A CORPORATION OF CALIFORNIA.

DESIGN FOR A PLATE OR SIMILAR ARTICLE.

Application filed September 2, 1925. Serial No. 14,693. Term of patent 14 years.

To all whom it may concern:

Be it known that I, WILLIAM G. JACKSON, a citizen of the United States, residing at Los Angeles, in the county of Los Angeles and State of California, have invented a new, original, and ornamental Design for a Plate or Similar Article, of which the following is a specification, reference being had to the accompanying drawing, forming part hereof.

The drawing is a plan view showing my new design.

I claim:

The ornamental design for a plate or similar article, as shown.

WILLIAM G. JACKSON.
